United States Patent Office

Des. 183,690
Patented Oct. 14, 1958

183,690

COMBINATION HOLDER AND CARRIER FOR MILK BOTTLES OR THE LIKE

Robert Graham, Burnley, England

Application May 31, 1957, Serial No. 46,461

Term of patent 7 years

(Cl. D58—5)

FIG. 1.

FIG. 2.

FIG. 3.

FIG. 4.

Fig. 1 is a side elevational view of a combination holder and carrier for milk bottles or the like, showing my new design.

Fig. 2 is a top plan view thereof.

Fig. 3 is a perspective view thereof, and

Fig. 4 is a bottom plan view thereof.

I claim:

The ornamental design for a combination holder and carrier for milk bottles or the like, as shown.
